UNITED STATES PATENT OFFICE.

LOUIS E. PARENT, OF CLAREMONT, NEW HAMPSHIRE, ASSIGNOR TO CLAREMONT WASTE MANUFACTURING COMPANY, A CORPORATION OF NEW HAMPSHIRE.

ROTARY CUTTER.

Application filed April 29, 1927. Serial No. 187,570

This invention relates to rotary cutters, and, more particularly, to rotary cutters adapted to cut flock used in the manufacture of shoddy.

In flock cutters heretofore provided, great danger from fire has existed due to the fact that as the rotating cylinder operates in conjunction with the stationary knives in the bed frame in cutting the flock, the parts may be brought to such a high temperature as to ignite the flock. Accordingly, it has been the practice in operating flock cutters to feed the same at full capacity until the cutting parts are believed to approach a dangerous warmth, and then to reduce the feed for several hours until the parts have cooled sufficiently. This has resulted, not only in numerous fires arising from bad judgment on the part of the operator, and causing danger, loss of material, damage to the knives and unnecessary labor, but in a frequent over-heating of the parts almost to the point of ignition, and frequent periods of operation at reduced speed. As a consequence, production has been kept down to a low daily production limit, the cooling time, which must follow overheating, reducing the output, and a fire requiring the total suspension of operation for hours, i. e. until the machine has cooled to a safe temperature.

This invention has for its object to provide an improved rotary cutter, and, more particularly, an improved flock cutter which not only reduces the danger from fire, but wherein loss of time due to over-heating of the parts, with resultant decreased production, is also reduced. A further object of the invention is to produce an improved cutter having an improved bed frame, and, more particularly, improved cooling means for the bed frame whereby the parts are maintained at a proper temperature for a longer time, in such manner as to enable the cutter to operate safely continuously for a longer time, and consequently to increase its production substantially per day. A further object of the invention is to provide improved cooling means for such a flock cutter, so constructed and arranged as to enable the above results to be obtained without interference with the other mechanism and while permitting the desired adjustment of the bed knives to be obtained. A still further object of the invention is to provide improved cooling water circulating means especially adapted to use

in connection with a flock cutter, whereby the desired circulation of cooling water to all necessary parts of the bed is maintained at the same time that all danger of the cooler becoming air-bound is overcome. These and other objects and advantages of this improved construction will, however, hereinafter more fully appear.

In the accompanying drawings, one embodiment which the invention may assume in practice is shown for purposes of illustration, the same being illustrated in connection with a flock cutter.

In these drawings,—

Fig. 1 is a vertical longitudinal section through this flock cutter equipped with the improvement;

Fig. 2 is a vertical transverse section on line 2—2 of Fig. 1;

Fig. 3 is a side elevation, partially in section, of the improved bed frame;

Fig. 4 is a longitudinal section on line 4—4 of Fig. 3;

Fig. 5 is a transverse section on line 5—5 of Fig. 3, and

Fig. 6 is a transverse section on line 6—6 of Fig. 3.

In this illustrative construction, the flock cutter comprises a usual legged supporting frame 1 carrying thereon in suitable journals 2 a rotary cutter or cylinder 3 which is provided with the usual spiral knives 4 adapted to cooperate with stationary knives 5 carried by the bed frame 6. This bed frame 6 is herein of improved construction herein-after more particularly described, and has depending flock discharge outlets 7 and 8 at its opposite ends adapted to receive the flock from either end of the cylinder depending upon the direction of rotation of the latter. As shown herein, the flock is adapted to be supplied to a hopper 9 above the cylinder, agitated therein by a suitable agitator 10, and fed to either desired end of the cylinder 3 by a reversible feed screw 11 supplying the material to end supply passages 12. Herein, the agitator 10 and feed screw 11 are also operated through suitable change speed driving mechanism, generally indicated at 13, 14 and reversely operable by the same power connection which drives the cylinder shaft 15. These feeding and driving connections, however, form no part of the present invention and accordingly need not be described more in detail herein.

Referring more particularly to the improved construction, it will be observed that the bed frame 6, while adjustable as usual about pivots 16 and carrying the usual chamber or socket 17 for the knives 5 and their usual bed plates, in which the knives are tightened laterally by means of set screws 18, is provided with a series of connected longitudinal and transverse cooling water passages 5 at points between the flock outlets 7 and 8. It will also be noted that means are also provided whereby it is made possible to maintain a circulation of cooling water from end to end of the bed frame, while it is still possible to adjust the knife blades toward or from the cylinder, as may be necessary, and to adjust the bed or frame as a whole without interfering with the normal functioning thereof.

Referring more especially to the water circulating structure, it will be observed that water is herein supplied at the end adjacent the flock outlet 7, through a bottom inlet 20 to a passage 21 which underlies one end of the bed socket 17 and extends upward in opposite directions from the pipe 20. This cooling water is then supplied through this passage to longitudinally extending passages 23, 24 extending along the sides of the knife bed, in such manner that the liquid may pass from end to end of the latter to cool the sides thereof and be discharged from the top of the end adjacent the flock outlet 8. It will also be observed that these channels 23, 24 are disposed below portions 25 of the bed frame curved to correspond in a slightly flatter curve than the working face of the knife bed and extending laterally along the opposite sides of the latter in proximity to the lower half of the cylinder 3. It will also be noted that a series of transverse passages 26 is provided connecting the longitudinal passages 23, 24 and underlying the knife bed so that the cool water may act not only to cool the sides of the knife bed and the flock and cylinder, due to its passage through the specially constructed chambers, but may also cool the bottom of the knife bed and flow freely from one longitudinal passage to the other. Here attention is also directed to the fact that between these passages 26 suitable slots or grooves 27 are formed at desirably spaced intervals, which not only serve the function of producing a greater radiation area, but also permit suitable adjusting screws 28 in the bottom of the bed to be adjusted in such manner as to vary the position of the knives 5 as may be necessary. After its flow through the longitudinal passages 23, 24 with their connected transverse passages 26, the cooling fluid is herein also discharged through outlets 29 and 30 (Fig. 6) in the form of pipes connected to the upper ends of the passages 23, 24 at a point above a transverse passage 31, similar to the passage 21 but adjacent the flock outlet 8, these upper outlets acting to prevent the cooler from becoming air-bound and

also allowing the escape of the heated water which rises to the top.

In the operation of my improved construction, it will be evident that water entering through the pipe 20 will pass through the passage 21 in opposite directions upwardly into the longitudinal passages 23, 24 and then pass longitudinally of those passages and transversely between the same through the passages 26, 31 and out through the outlets 29 and 30. Thus, when a continuous supply of cooling water is maintained, substantially the whole working or heating area of the knife bed is maintained at the desired temperature. More particularly, it will be observed that not only is the knife bed cooled under its bottom by the flow through the transverse channels 21, 26 and 31 and radiation in the grooves 27, but that the same is further cooled along its sides by the flow through the longitudinal channels 23, 24. It will also be observed that due to the special shaping of the longitudinal channels 23, 24 it is made possible to cool the concave area at either side of the stationary knives 5 and thus to reduce the temperature of the flock which is packed in above these channels and also effect some cooling of the cylinder and the knives thereon. These are also cooled by the cooling of the knives 5 and their bed.

In the use of my improvement, it is found possible, as compared with the uncooled machine previously standard in the flock cutter art, to triple the productive capacity of the cutter. This is due to the effective cooling obtained and to the longer continuous operation at full capacity made possible thereby before overheating occurs, as well as to the cooling effect during reduced operation. Further, where a group of machines is operated, as is usual in this art, not only is the average productive capacity per machine increased as stated, but the danger from fire heretofore experienced is reduced. At the same time, the number of hours of enforced machine idleness required to permit the machine to cool after a fire and amounting to three or four hours, is reduced. There is also a corresponding reduction in the loss of labor incident to fires and in the supervision necessary to prevent fires. Thus, in addition to substantially increasing the productive capacity of the machine, the labor cost is substantially reduced, as a single operator is able to take care of a substantially larger number of machines.

Through the provision of suitable removable plugs 33, 32 access is also permitted to the various longitudinal or transverse passages as may be necessary for cleaning or the like. Attention is also directed to the fact that the improved cooling mechanism is herein formed integral not only with the support for the knife bed, but also with the flock outlets 7 and 8 at the ends of the bed, thereby producing an exceedingly simple and

rugged construction. These and other advantages of the improved construction will, however, be clearly apparent to those skilled in the art.

5 While in this application is specifically described one embodiment which the invention may assume in practice, it will be understood that the invention is not limited thereto, but may be modified and embodied in various 10 other forms without departing from its spirit or the scope of the appended claims.

What I claim as new and desire to secure by Letters Patent is:—

1. The combination with a flock cutter 15 having a knife carrying concave bed, of water circulating means for the latter maintaining a cooling flow close to the bases of the knives therein.

2. In a rotary cutter, a tool carrying cylinder, a cooperating tool carrying bed, and cooling means for the latter permitting adjustment of the tools in said bed without disturbing the cooling flow.

25 3. In a rotary cutter, a tool carrying cylinder, a cooperating tool carrying bed, and cooling means for the latter cooling the sides and bottom of said bed.

4. In a rotary cutter, a tool carrying cylinder, a cooperating tool carrying bed, and cooling means for the latter including passage means cooling one side of said bed and the material as it passes to the side of the latter.

5. In a rotary cutter, a tool carrying cylinder, a cooperating tool carrying bed, and cooling means for the latter cooling the bottom and sides of said bed and the material at each side thereof.

40 6. In a rotary cutter, a tool carrying cylinder, a cooperating tool carrying bed, and cooling means for the latter including passage means having a cooled surface along one side of said bed and a relatively laterally disposed cooled surface adjacent said cylinder at that side of said bed.

45 7. In a rotary cutter, a reversible tool carrying cylinder, a cooperating tool carrying bed, and cooling means for the latter cooling the sides and bottom of said bed and the material passing to said bed in either direction of rotation of said cylinder.

8. In a rotary cutter, a tool carrying cylinder, a cooperating tool carrying bed, and cooling means for the latter having longitudinal passages along the sides of said bed and bottom cooling means connecting said passages.

40 9. In a rotary cutter, a tool carrying cylinder, a cooperating tool carrying bed, and cooling means for the latter having a series of communicating cooling water passages cooling the bottom of said bed and provided with a bottom inlet and a top discharge.

45 10. In a rotary cutter, a tool carrying cylinder, a cooperating tool carrying bed, and

cooling means for the latter including longitudinal passages along the sides of said bed and provided with a bottom inlet and a top discharge at opposite ends of said bed.

11. In a rotary cutter, a tool carrying cylinder, a cooperating tool carrying bed, and cooling means for the latter having longitudinal 70 passages along the sides of said bed and bottom cooling means connecting said passages comprising a plurality of transverse 75 passages.

12. In a rotary cutter, a tool carrying cylinder, a cooperating tool carrying bed, and cooling means for the latter having longitudinal 80 passages along the sides of said bed and bottom cooling means connecting said passages comprising a plurality of transverse passages separated by transverse slots.

13. In a rotary cutter, a tool carrying cylinder, a cooperating tool carrying bed, and cooling means for the latter having longitudinal 85 passages along the sides of said bed and bottom cooling means connecting said passages, said cooling means being provided with a bottom inlet and a top outlet. 90

14. In a rotary cutter, a tool carrying cylinder, a cooperating tool carrying bed, a support therefor having a bed receiving socket therein, and cooling means in the side and bottom of said socket cooling the side and 95 bottom of said bed.

15. In a rotary cutter, a tool carrying cylinder, a cooperating tool carrying bed, a support therefor having a bed receiving socket 100 therein, and cooling means in the sides and bottom of said socket cooling the sides and bottom of said bed and also having a laterally extending cooled surface at each side of said bed.

16. In a rotary cutter, a tool carrying cylinder, a cooperating tool carrying bed, cooling means for the latter, and means whereby the tools in said bed may be adjusted while said cooling means remains in position. 105

17. In a rotary cutter, a tool carrying cylinder, a cooperating tool carrying bed, cooling means for the latter, and means whereby the tools in said bed may be adjusted from the bottom of said bed while said cooling means remains in position. 110

18. In a rotary cutter, a tool carrying cylinder, a cooperating tool carrying bed, and cooling means for the latter having aperture forming means increasing the radiating surface while permitting adjustment of the tools 115 in said bed from the bottom of the latter. 120

19. In a rotary cutter, a tool carrying cylinder, a cooperating tool carrying bed, cooling means for the latter cooling the sides and bottom of said bed, and means whereby the tools in said bed may be adjusted laterally or from the bottom of said bed without disturbing said cooling means. 125

20. In a rotary cutter, a tool carrying cylinder, a cooperating tool carrying bed, a sup-

port for the latter having discharge outlets at its opposite ends and a bed socket intermediate said outlets, and cooling means for said socket in said support between said outlets and having provision whereby the tools in said bed may be adjusted from the exterior of the cooling means.

21. In a rotary cutter, a tool carrying bed, and cooling means for the latter having longitudinal passages along the edges of said bed, transverse connecting passage means between said passages, transverse slots dividing said transverse passage means into a series of passages, inlet means connected to the bottom of one of said passages at one end of the cooling means, and outlet means connected at the opposite end of the cooling means to the tops of said longitudinal passages.

22. In a rotary cutter, a tool carrying bed, means forming a socket receiving the same, and cooling means in the socket having longitudinal passages along the sides of said bed and cooling means connecting said passages and cooling the bottom of said bed.

23. In a rotary cutter, a tool carrying bed, and a support therefor having a bed receiving socket therein, said support having cooling means for the sides and bottom of said socket cooling the sides and bottom of said bed and the material passing to and from the bed.

24. In a rotary cutter, a support having a bed receiving socket therein, said support having water passages forming cooling means for the sides and bottom of said socket for cooling the sides and bottom of a tool carrying bed seated therein, and having a bottom inlet and a top outlet, and said support also having apertures in its bottom permitting access to the bed tools.

25. In a rotary cutter, a tool carrying cylinder, a cooperating tool carrying bed, and cooling means for the bottom of the latter having slots therein increasing the radiating surface and permitting access to the tools in said bed from the bottom of the latter.

26. In a rotary cutter, a tool carrying cylinder, a cooperating tool carrying bed, and cooling means for the bottom of the latter having a series of transverse slots therein increasing the radiating surface and permitting access to the tools in said bed from the bottom of the latter.

27. In a rotary cutter, a tool carrying cylinder, a cooperating tool carrying bed, a support therefor having a bed receiving socket therein, and cooling means cooling the sides and bottom of said bed having transverse slots in the bottom thereof permitting access to the tools in said bed.

28. In a rotary cutter, a tool carrying cylinder, a cooperating tool carrying bed, a support for the latter having discharge outlets at its opposite ends and a bed socket intermediate said outlets and the sides of said

support, and cooling means for the sides and bottom of said socket in said support between said outlets.

29. In a rotary cutter, a tool carrying cylinder, a cooperating tool carrying bed, a support for the latter having discharge outlets at its opposite ends and a bed socket intermediate said outlets, and cooling means for said bed in said support between said outlets and having transverse slots in the bottom thereof permitting access to said tools in said bed from the bottom of the latter.

30. In a rotary cutter, a tool carrying socket having longitudinal cooling water passages along the sides thereof and a plurality of transverse connecting passage means between said passages.

31. In a rotary cutter, a tool carrying cylinder, a cooperating tool carrying bed, and cooling means for the latter having longitudinal cooling water passages along the edges of said bed and transverse connecting passage means between said passages and transverse slots dividing said transverse passage means.

32. In a rotary cutter, a tool carrying cylinder, a cooperating tool carrying bed, and cooling means for the latter having longitudinal cooling water passages along the edges of said bed, transverse connecting passage means between said passages, inlet means connected to the bottom of said transverse means, and outlet means connected to the top of said longitudinal passages.

33. In a rotary cutter, a tool carrying cylinder, a cooperating tool carrying bed, and cooling means for the latter having longitudinal passages along the edges of said bed, transverse connecting passage means between said passages, inlet means connected to the bottom of said transverse means, and outlet means connected to the top of said longitudinal passages, said inlet and outlet means being disposed at opposite ends of said cooling means.

34. In a rotary cutter, a tool carrying cylinder, a cooperating tool carrying bed, and cooling means for the latter having longitudinal passages along the edges of said bed, transverse connecting passage means between said passages, and transverse slots dividing said transverse passage means into a series of wide passages and a narrower passage at each end of said cooling means.

35. In a rotary cutter, a tool carrying cylinder, a cooperating tool carrying bed, and cooling means for the latter having longitudinal passages along the edges of said bed, transverse connecting passage means between said passages, transverse slots dividing said transverse passage means into a series of passages, inlet means connected to the bottom of one of said passages at one end of the bed, and outlet means connected at the opposite end of the cooling means to the tops of said longitudinal passages.

36. The combination with a flock cutter having a knife carrying concave bed, of water circulating means for the latter maintaining a cooling flow close to the bases of the knives therein and transversely and longitudinally of the bed.

5 37. The combination with a flock cutter having a knife carrying concave bed, of water

circulating means for the latter maintaining a cooling flow close to the bases of the knives therein and transversely and longitudinally 10 of the bed.

In testimony whereof I affix my signature.

LOUIS E. PARENT.
